MARY HAMILTON AND GERALD JOHN SUTTON, OF LONDON, ENGLAND

PLAITING DEVICE

Application filed September 18, 1928, Serial No. 306,683, and in Great Britain April 26, 1928.

This invention consists in improvements in or relating to plaiting devices, and has for its object to provide a device whereby a plait or plaits can be produced and pressed down in textile material or the like by relative movement between the device and the material in the direction of the lengths of the plaits.

The present invention accordingly comprises, in combination, two parts which are to be applied respectively to opposite sides of the material and which co-operate together to afford for each plait a slot, and a guide or guides to engage the material and to press it into the slot to produce first an upstanding fold of material and then to overturn that fold on or towards the surface of the material, whereafter the fold can be pressed into a flat plait. Preferably, means is provided for pressing the fold after it has been overturned.

In one preferred form of the invention, the means to form a fold of material is constituted by grooved rollers on both parts of the device. The rollers are conveniently so disposed as to traverse the material one in advance of the other so that an annular rib on one roller enters a groove in the companion roller.

In order that the invention may be more clearly understood, two preferred examples of the invention will now be described with the aid of the accompanying drawings, in which—

Figure 1 is a plan, looking from above, of the two parts of the device in their operative relationship;

Figure 2 is a central elevation on the line 2—2 of Figure 3;

Figure 3 is an under plan view;

Figure 4 is a perspective view of a guiding element of the device;

Figure 5 is a view, similar to Figure 1, of a modified construction;

Figure 6 is a section on the line 6—6 of Figure 5;

Figure 7 is an under plan view of the device illustrated in Figures 5 and 6;

Figure 8 is a perspective view of a guid-

ing element for the modification illustrated in Figures 5, 6 and 7, and

Figure 9 is a view, similar to Figure 8, of a guiding element designed to produce a box-plait.

Like reference numerals indicate like parts in the several figures of the drawings.

Referring first of all to the construction illustrated in Figures 1 to 4, the two portions of the device are indicated generally by the reference numerals 10 and 11, the portion 10 being the upper portion and the portion 11 being the lower portion. In the upper portion there is a grooved roller 12 presenting several relatively deep grooves, and in the lower portion 11 there is a similar roller 13, the ribs or flanges of which will pass into the grooves of the roller 12. The material to be plaited passes between the two rollers, that is to say, the portion 11 is placed beneath the material and the portion 10 above the material, and the portions of the material will then be forced into the grooves by the interengagement of the two rollers. The upper roller will have as many channels or grooves as it is desired there shall be plaits produced simultaneously. The roller is mounted to rotate in brackets 14 depending as lugs from the frame of the part 10, which is constituted mainly of sheet material bent into the form shown in the drawings. Part of the frame comprises a flat presser-plate 15 which, in the example illustrated, is adapted to receive the nose of a flat-iron 150 or like device. The portion 10 is constituted by two parts, one of which comprises the presser portion 15 and an upstanding end portion 16, and the other portion 11 comprises a forwardly-extending part 17 (the use of which will be described later), a transversely-disposed portion 18, and a slotted guide portion 19. The two parts are connected together by nuts and bolts or screws, such as 200, by which the abutting portions 16 and 18 are clamped together. The guide portion 19, the form of which is shown clearly in Figures 2 and 3, affords a plurality of spaced forwardly-extending guide elements or tongues, each adapted to enter a fold of the material. Behind the guide tongues 19

there is a plate 20, shown in detail in Figure 4. The plate is formed with a number of saw-gates or slots 21 which are inclined transversely with respect to the direction of movement of the device and into which folds of the material are led by means of the guides 19. The folds are upstanding folds as they leave the guides 19 and by their passage through the slots 21, the folds are each turned over towards the surface of the material owing to the inclination of the slots. The folds thus overturned will be passed beneath the presser-plate 15. Any plate such as the plate 20, having slots opening in an edge of the plate, will be referred to herein as a saw-gated member.

In the companion portion 11, which is intended normally to be beneath the material, the roller 13 is borne in upstanding lugs 22 projecting from a flat base portion 23. At its trailing edge, the latter is formed as, or has secured to it, a number of tongues 24, each of which projects into a groove in the roller 12. These tongues terminate just short of the guiding tongues 19 and aid the latter in maintaining and guiding the folds of the material as they are led to the overturning slots 21.

In order to position the two portions 10 and 11 of the device relatively to one another while they are in operation, the forward extension 17 of the upper portion 10 is provided at its front end with an overhanging lip 25 which not only overhangs and engages an abutment such as the nose of the under part, but it is also so shaped as to guide and assist in tensioning the material as it is led between the two portions of the device.

The slotted plate 21 is held in position 40 between the portion 26 of the sheet of material from which the presser surface 15 extends and spring tongues 27 formed by cutting and bending the material at the margins of the portion 26. The plate 20 is, therefore, 45 readily removable and may be replaced by a plate having slots of other form, or the plate 20 may be reversed in position so as to overturn the plaits in the opposite direction.

The modification described in Figures 5 to 8 is in the main similar to that already described. The principal difference consists in the fact that the tongues 19 and the fingers between the slots in the plate 20 are now formed in one piece by means of a slotted angled-plate illustrated in detail in Figure 8. An upstanding margin 30 of this plate is adapted to be inserted between the transverse wall 16 of the upper portion 11 and one or more leaf-springs 31 secured to and depending from the upper wall 17.

The angled portion of the plate comprises a forwardly-directed sloping portion 32 in which there are formed slots 33 whose centre lines extend longitudinally of the plaiting device; that is to say, planes containing these

centre lines are parallel or coincident with planes passing through the middle of the grooves in the roller 12. The other surface 34 of the angled portion of the plate is formed with inclined slots 35 comprising 70 continuations of the slots 33 and corresponding to the slots 21 of the plate 20.

Whereas in the first described example overhanging and rearwardly-extending arms 29 are provided for engaging the flat-iron 75 150, the present example comprises two arms 36 hinged about a stud 37 to adjust the distance between them. The arms 36 are intended also to engage over the flat iron and at their forward extensions the arms are slotted to engage a stud 38. After they have been adjusted the arms are clamped in position by means of a nut 39 which screws down on to the stud 38.

It will be appreciated that the numbers of 85 the grooves in the rollers 12 and 13 may be varied to suit the requirements of the plaiting attachment, and a corresponding number of slots in the plate such as 20 or its equivalent, and a corresponding number of guide 90 tongues on the two parts will be provided. In one extreme construction the rollers and slots may be so arranged as to produce only one plait at a time.

Means may be provided, although not 95 shown in the example illustrated, for enabling the degree of meshing between the rollers of the two parts to be adjusted to form folds of material of a greater or lesser depth and thus to form narrower or wider plaits.

It is not necessary to employ rollers as the 100 two interengaging grooved members on the two parts of the device. For instance, a grooved plate on one part could have the material pressed into it by means of tongues or fingers or projections from another grooved plate on the other part; or a grooved plate or a plurality of tongues on one part could be employed in co-operation with a grooved roller on the other part.

Again, instead of employing a separate 110 flat iron to which the device is to be used as an attachment, a heating element can be included in either or both of the parts of the device, preferably in the portion 11, and a handle attached to the latter part will then enable the device to be employed as an ironing and plaiting unit.

When the device is formed in the manner 120 specifically described above, the nose of the iron pressing the upper part, or the upper part itself as an iron device, may be pushed along over an ironing board or like support, and, in so doing, the under part will be propelled on the opposite side of the material 125 thus forming the plaits by hand.

Alternatively, the device could be affixed in position and the material drawn through it. For instance, the device could be held in a fixed frame and the material plaited in the 130

length by being drawn from a roll or supply of material on to a winding roller, power being provided in any usual manner.

As a further alternative, the device can be mounted on guides so that it is positively guided relatively with respect to the material.

The two parts of the apparatus could be detachably connected with one another in a more positive manner by means of side links, for example, provided that the dimension between the side links is sufficiently great to take in the width of the material.

The rollers or grooved plates and guide fingers and overturning slots can be made up as replacable units so that when it is desired to form plaits of different dimensions or in different numbers, the required roller or plate and guide fingers and overturning slots can be selected accordingly.

Several elements forming part of the apparatus might be independently replaceable or replaceable in a unitary assembled condition.

In Figure 9 a modification is illustrated of a guide-plate similar to that of Figure 8. In this form the inclined portions 35 of the slots are oppositely inclined on the two halves of the plate so that the plaits on one half of the line of plaits will be overturned in one direction and the remaining plaits will be overturned in the opposite direction. Thus at the middle a box-plait will be produced. In a similar manner the inclined guide slots 21 in the plate 20, Figure 4, may be formed to produce a box-plait having on each side of it oppositely turned-over plaits.

We claim:-

1. A device for producing plaits in textile material by relative movement between the device and the material in the direction of the lengths of the plaits said device comprising in combination two parts which are to be applied respectively to opposite sides of the material, co-operating channelled rollers one in each part whereof an annular rib on one roller is adapted to enter a channel in the companion roller, a guide to maintain a fold of the material in the channel of said latter roller, and means thereafter to overturn the upstanding fold of material so formed during the said relative movement.

2. A device for producing plaits in textile material by relative movement between the device and the material in the direction of the lengths of the plaits, said device comprising in combination two parts which are to be applied respectively to opposite sides of the material, a channelled roller in each part which rollers are so disposed to traverse the material one in advance of the other with an annular rib of one roller entering a channel on the companion roller, a slotted guide-plate trailing the rearmost roller and having for each plait a slot to receive the fold of material that is pressed up into the channel in the

roller and to overturn said fold as the device is traversed over the material.

3. A device for producing plaits in textile material by relative movement between the device and the material in the direction of the lengths of the plaits, said device comprising in combination two parts which are to be applied respectively to opposite sides of the material, a channelled roller in each part, which rollers are so disposed as to traverse the material one in advance of the other with an annular rib of one roller entering a channel of the companion roller, a slotted guide-plate trailing the rearmost roller and having for each plait a slot to receive the fold of material that is pressed up into the channel in the roller and to overturn said fold as the device is traversed over the material and a guide-finger entering the groove in the rearmost roller to maintain the fold of material therein and to lead it into the guide-slot.

4. A device for producing plaits in textile material by relative movement between the device and the material in the direction of the lengths of the plaits, said device comprising two parts which are to be applied respectively to opposite sides of the material, one of said parts comprising a channelled roller and for each plait an overturning guide-slot, and the other part comprising a channelled roller and for each plait a guide-finger to enter the groove of the companion roller, for the purpose described.

5. A device for producing plaits in textile material by relative movement between the device and the material in the direction of the lengths of the plaits, said device comprising in combination two parts which are to be applied respectively to opposite sides of the material, co-operating channelled rollers, one in each part, whereof an annular rib on one roller is adapted to enter a channel in the companion roller, a guide to maintain a fold of material in the channel on said roller and a removable saw-gated guide-member which has saw-gates that are inclined across the line of relative movement and into which the folds of material are led and by which they are overturned.

6. A device for producing a plait in textile material by relative movement between the device and the material in the direction of the length of the plait, said device comprising in combination two parts which are to be applied respectively to opposite sides of the material and which together afford a slot and a guide to engage the material and to press it into the slot to produce during the said relative movement first an upstanding fold of material, then to overturn that fold on to or towards the surface of the material, and an extension from the upper part that overhangs an abutment at the forward end of the under part and is so shaped as to

guide and assist in tensioning the material as it is led between the two parts.

7. A device for producing plaits in textile material by relative movement between the device and the material in the direction of the lengths of the plaits, said device comprising in combination two parts whereof the under one comprises a channelled roller and rearwardly-extending guide tongues in line with channels on a roller in the companion part, and the companion part comprises a channelled roller, a pressing surface in rear of said roller and a slotted guide element interposed between the roller and the pressing surface, whereof the leading portions of the slots present vertically-disposed guide walls in line with the ribs on the roller and the rear portions of the slots are inclined in a transverse plane across the line of relative movement.

10 8. A device for producing plaits in textile material by relative movement between the device and the material in the direction of the lengths of the plaits, said device comprising in combination two parts whereof the under one comprises a channelled roller and rearwardly-extending guide tongues in line with channels on a roller in the companion part, and the companion part comprises a channelled roller, a pressing surface in rear of said roller and a slotted guide element interposed between the roller and the pressing surface, whereof the leading portions of the slots present vertically-disposed guide-walls in line with the ribs of the roller and these portions of the slots are inclined in a transverse plane across the line of relative movement, that portion at least of the guide-element containing the inclined 35 slots being detachably secured in position.

15 9. A device for producing plaits in textile material by relative movement between the device and the material in the direction of the lengths of the plaits, said device comprising in combination two parts whereof the under one comprises a channelled roller and rearwardly-extending guide tongues in line with the channels on a roller in the companion part and the companion part comprises a channelled roller, a pressing surface in rear of said roller, and between the roller and pressing surface there are forwardly-extending tongues in line with and adjacent the ribs on the roller and behind the tongues a 50 slotted guide-member whereof the slots are inclined across the line of relative movement.

20 10. A device for producing plaits in textile material by relative movement between the device and the material in the direction of the lengths of the plaits, said device comprising in combination two parts whereof the under part comprises a sheet metal casing in which is supported a channelled roller and guide-tongues disposed in rear of said roller and in 55 line with channels on a roller in the com-

panion part, and the companion part comprises a sheet metal casing in which is supported a channelled roller whereof the ribs enter channels in the first-named roller, forwardly-extending guide-tongues adjacent the ribs of the second-mentioned roller, a guide-member having in its slots that are inclined across the line of said relative movement and constitute continuations of the spaces between the forwardly-extending guide-tongues, and a pressing surface in rear of said inclined slots.

70 11. A device for producing plaits in textile material by relative movement between the device and the material in the direction of the lengths of the plaits, said device comprising in combination two parts whereof the under part comprises a sheet metal casing in which is supported a channelled roller and guide-tongues disposed in rear of said roller 80 and in line with channels on a roller in the companion part, and the companion part comprises a sheet metal casing in which is supported a channelled roller whereof the ribs enter channels in the first-named roller, forwardly-extending guide-tongues adjacent the ribs of the second-mentioned roller, a guide-member having in its slots that are inclined across the line of said relative movement and constitute continuations of the spaces between the forwardly-extending guide-tongues, a pressing surface in rear of said inclined slots, and an extension from the casing of the said companion part that projects forwardly to overhang an abutment at the forward end of the first-named 90 part and is so shaped as to guide and assist in the tensioning of the material as it is led between the two parts.

95 12. A device for producing plaits in textile material by relative movement between the device and the material in the direction of the lengths of the plaits, said device comprising in combination two independent parts which have no mechanical connection with 100 each other, and which are to be applied respectively to opposite sides of the material, cooperating channelled rollers one in each part whereof an annular rib on one roller is adapted to enter a channel in the companion roller, a guide to maintain a fold of the material in the channel of said latter roller, and means thereafter to overturn the upstanding fold of material so formed during the said 110 relative movement, movement of one part relative to the material being produced by the pressure of the other part acting on it through the interposed material.

115 13. A device for producing plaits in textile material by relative movement between the device and the material in the direction of the lengths of the plaits, said device comprising in combination two independent parts which have no mechanical connection with 120

125

- each other and which are to be applied respectively to opposite sides of the material, a channelled roller in each part which rollers are so disposed as to traverse the material 5 one in advance of the other with an annular rib of one roller entering a channel on the companion roller, a slotted guide-plate trailing the rearmost roller and having for each plait a slot to receive the fold of material 10 that is pressed up into the channel in the roller and to overturn said fold as the device is traversed over the material, movement of one part relative to the material being produced by the pressure of the other part acting on it through the interposed material. 15
14. A device for producing plaits in textile material by relative movement between the device and the material in the direction of the lengths of the plaits, said device comprising in combination two independent parts which have no mechanical connection with each other and which are to be applied respectively to opposite sides of the material, a channelled roller in each part, which rollers 20 are so disposed as to traverse the material one in advance of the other with an annular rib of one roller entering a channel of the companion roller, a slotted guide-plate trailing the rearmost roller and having for each 25 plait a slot to receive the fold of material that is pressed up into the channel in the roller and to overturn said fold as the device is traversed over the material and a guide-finger entering the groove in the rearmost roller 30 to maintain the fold of material therein and to lead it into the guide-slot, movement of one part relative to the material being produced by the pressure of the other part acting on it through the interposed material. 35
15. A device for producing plaits in textile material by relative movement between the device and the material in the direction of the lengths of the plaits, said device comprising two independent parts which have 40 no mechanical connection with each other, and which are to be applied respectively to opposite sides of the material, one of said parts comprising a channelled roller and for each plait an overturning guide-slot, and the 45 other part comprising a channelled roller and for each plait a guide-finger to enter the groove of the companion roller, for the purpose described, movement of one part relative to the material being produced by the 50 pressure of the other part acting on it through the interposed material. 55
16. A device for producing plaits in textile material by relative movement between the device and the material in the direction of 60 the length of the plaits, said device comprising in combination two independent parts which have no mechanical connection with each other which are to be applied respectively to opposite sides of the material, 65 and which together afford for each plait a 70 removable saw-gated guide member in which the saw-gates are inclined across the line of relative movement, for the purpose described, movement of one part relative to the material being produced by the pressure of the other part acting on it through the interposed material. 75
17. A device for producing plaits in textile material by relative movement between the device and the material in the direction of the lengths of the plaits, said device comprising in combination two independent parts which have no mechanical connection with each other and which are to be applied respectively to opposite sides of the material, co-operating channelled rollers, one in each part, whereof an annular rib on one roller is adapted to enter a channel in a companion roller, a guide to maintain a fold of material in the channel on said roller and a removable saw-gated guide-member which has saw-gates that are inclined across the line of relative movement and into which the folds of material are led and by which they are overturned, movement of one part relative to the material being produced by the pressure of the other part acting on it through the interposed material. 80
18. A device for producing a plait in textile material by relative movement between the device and the material in the direction of the length of the plait, said device comprising in combination two independent parts which have no mechanical connection with each other which are to be applied respectively to opposite sides of the material, and which together afford for each plait a slot in which an upstanding fold of material is produced and a removable saw-gated guide-member which has saw-gates that are inclined across the line of relative movement and into which the upstanding fold is led and by which it is overturned during said relative movement, movement of one part relative to the material being produced by the pressure of the other part acting on it through the interposed material. 90
19. A device for producing plaits in textile material by relative movement between the device and the material in the direction of the lengths of the plaits, said device comprising in combination two independent parts which have no mechanical connection with each other and which are to be applied respectively to opposite sides of the material, 95 co-operating channelled rollers, one in each part, whereof an annular rib on one roller is adapted to enter a channel in the companion roller, a guide to maintain a fold of material in the channel in said latter roller, and a removable saw-gated guide-member which has saw-gates that are inclined across the line of relative movement and which receive the folds of material and overturn them during said relative movement, move- 100

ment of one part relative to the material being produced by the pressure of the other part acting on it through the interposed material.

5. 20. A device for producing a plait in textile material by relative movement between the device and the material in the direction of the length of the plait, said device comprising in combination two independent parts which have no mechanical connection with each other which are to be applied respectively to opposite sides of the material and which together afford a slot and a guide to engage the material and to press it into the slot to produce during the said relative movement first an upstanding fold of material, then to overturn that fold on to or towards the surface of the material, and an extension from the upper part that overhangs an abutment at the forward end of the under part and is so shaped as to guide and assist in tensioning the material as it is led between the two parts, movement of one part relative to the material being produced by the pressure of the other part acting on it through the interposed material.

21. A device for producing plaits in textile material by relative movement between the device and the material in the direction of the lengths of the plaits, said device comprising in combination two independent parts which have no mechanical connection with each other, whereof the under one comprises a channelled roller and rearwardly-extending guide tongues in line with channels on a roller in the companion part, and the companion part comprises a channelled roller, a pressing surface in rear of said roller and a slotted guide element interposed between the roller and the pressing surface, whereof the leading portions of the slots present vertically-disposed guide walls in line with the ribs on the roller and the rear portions of the slots are inclined in a transverse plane across the line of relative movement, movement of one part relative to the material being produced by the pressure of the other part acting on it through the interposed material.

22. A device for producing plaits in textile material by relative movement between the device and the material in the direction of the lengths of the plaits, said device comprising in combination two independent parts which have no mechanical connection with each other whereof the under one comprises a channelled roller and rearwardly-extending guide tongues in line with channels on a roller in the companion part, and the companion part comprises a channelled roller, a pressing surface in rear of said roller, and a slotted guide element interposed between the roller and the pressing surface, whereof the leading portions of the slots present vertically-disposed guide-walls in line with the ribs of the roller and the rear portions of the slots

are inclined in a transverse plane across the line of relative movement, that portion at least of the guide-element containing the inclined slots being detachably secured in position, movement of one part relative to the material being produced by the pressure of the other part acting on it through the interposed material.

23. A device for producing plaits in textile material by relative movement between the device and the material in the direction of the lengths of the plaits, said device comprising in combination two independent parts which have no mechanical connection with each other whereof the under one comprises a channelled roller and rearwardly-extending guide tongues in line with the channels on a roller in the companion part and the companion part comprises a channelled roller, a pressing surface in rear of said roller, and between the roller and pressing surface there are forwardly-extending tongues in line with and adjacent the ribs on the roller and behind the tongues a slotted guide-member whereof the slots are inclined across the line of relative movement, movement of one part relative to the material being produced by the pressure of the other part acting on it through the interposed material.

24. A device for producing plaits in textile material by relative movement between the device and the material in the direction of the lengths of the plaits, said device comprising in combination two independent parts which have no mechanical connection with each other whereof the under part comprises a sheet metal casing in which is supported a channelled roller and guide-tongues disposed in rear of said roller and in line with channels on a roller in the companion part, and the companion part comprises a sheet metal casing in which is supported a channelled roller, whereof the ribs enter channels in the first-named roller, forwardly-extending guide-tongues adjacent the ribs of the second-mentioned roller, a guide-member having in it slots that are inclined across the line of said relative movement and constitute continuations of the spaces between the forwardly-extending guide-tongues, and a pressing surface in rear of said inclined slots, movement of one part relative to the material being produced by the pressure of the other part acting on it through the interposed material.

25. A device for producing plaits in textile material by relative movement between the device and the material in the direction of the lengths of the plaits, said device comprising in combination two independent parts which have no mechanical connection with each other, whereof the under part comprises a sheet metal casing in which is supported a channelled roller and guide-tongues disposed in rear of said roller and in line with

channels on a roller in the companion part, and the companion part comprises a sheet metal casing in which is supported a channelled roller whereof the ribs enter channels
5 in the first-named roller, forwardly-extending guide-tongues adjacent the ribs of the second-mentioned roller, a guide-member having in it slots that are inclined across the line of said relative movement and constitute
10 continuations of the spaces between the forwardly-extending guide-tongues, a pressing surface in rear of said inclined slots, and an extension from the casing of said companion part that projects forwardly to overhang
15 an abutment at the forward end of the first-named part and is so shaped as to guide and assist in the tensioning of the material as it is led between the two parts, movement of one part relative to the material being produced by the pressure of the other part acting
20 on it through the interposed material.

26. A device for producing plaits in textile material by relative movement between the device and the material in the direction of
25 the lengths of the plaits, said device comprising in combination two parts which are to be applied respectively to opposite sides of the material, cooperating channelled rollers one in each part, whereof an annular rib on one
30 roller is adapted to enter a channel in the companion roller, a guide to maintain a fold of the material in the channel of said latter roller, means thereafter to overturn the up-standing fold of material so formed during
35 the said relative movement, and a presser surface on one of said parts located to press on said overturned folds during the aforesaid relative movement.

In testimony whereof we have signed our
40 names to this specification.
